Primary Examiner — Katrina N Gonzalez*(74) Attorney, Agent, or Firm* — Wright Lindsey Jennings, LLP; Meredith Lowry(57) **CLAIM**

The ornamental design for a dog training dummy, as shown and described.

DESCRIPTION

FIG. 1 is a front perspective view of a dog training dummy; FIG. 2 is a rear perspective view thereof; FIG. 3 is a right side view thereof, the left side being a mirror image thereof;

FIG. 4 is a top view thereof, the bottom view being a mirror image thereof;

FIG. 5 is a front elevation view thereof; and,

FIG. 6 is a rear elevation view thereof.

The broken lines in the drawings illustrate environment structure that forms no part of the claimed design.

1 Claim, 3 Drawing Sheets(56)
